UNITED STATES PATENT OFFICE

146,705

DESIGN FOR AN ELECTRIC SADIRON

Maurice J. Denning, St. Charles, Mo., assignor to
The Emerson Electric Manufacturing Company, St. Louis, Mo., a corporation of Missouri

Application August 9, 1945, Serial No. 121,331

Term of patent 14 years

(Cl. 49—6)

To all whom it may concern:

Be it known that the undersigned, Maurice J. Denning, a citizen of the United States, residing at St. Charles, Missouri, has invented a new, original, and ornamental Design for an Electric Sadiron, of which the following is a specification, reference being had to the accompanying drawing, forming a part thereof, in which:

Fig. 1 is an elevational view of one side of an electric sadiron, showing my new design;

Fig. 2 is an elevational view of the other side thereof;

Fig. 3 is a top plan view thereof; and
Fig. 4 is a rear elevational view thereof.

I claim:

The ornamental design for an electric sadiron, substantially as shown.

MAURICE J. DENNING.
